[57] **CLAIM**

The ornamental design for a dispenser housing for the release of chemicals into a toilet bowl basin, as shown and described.

DESCRIPTION

FIG. 1 is a top, front and left side perspective view of a dispenser housing for the release of chemicals into a toilet bowl basin showing our new design;

FIG. 2 is a top, front and right side perspective view thereof, with the front portion shown pivoted to an open position;

FIG. 3 is a front elevational view thereof;

FIG. 4 is a front elevational view thereof, with the front portion shown pivoted to an open position;

FIG. 5 is a left side elevational view thereof;

FIG. 6 is a right side elevational view thereof;

FIG. 7 is a rear elevational view thereof;

FIG. 8 is a top plan view thereof; and

FIG. 9 is a bottom plan view thereof.

The broken-line showing of the chemical container is for illustrative purposes only and forms no part of the claimed invention.
